SENSITIVE RELAY MECHANISM

Benjamin Cyr, Minneapolis, Minn., assignor to
 Minneapolis-Honeywell Regulator Company,
 Minneapolis, Minn., a corporation of Delaware

Application October 6, 1941, Serial No. 413,789

13 Claims. (Cl. 200—56)

The present invention relates to a sensitive relay mechanism and particularly to that type of mechanism wherein the operation of a motor is controlled in accordance with the position of a pointer of a delicate galvanometer.

Such mechanism usually includes a device for periodically clamping the galvanometer pointer. Each time the pointer is clamped, a member is moved into engagement with the pointer, and a switch mechanism is then operated in accordance with the position obtained by the member. When such a device is used to control a motor, the switch arrangement usually operates the motor in one direction or the other, depending upon the deflection of the galvanometer from a center position. With such mechanism it is customary to tilt a member in accordance with the position of a galvanometer needle and thereafter move said member through a fixed path. A switch mechanism, which is accordingly tilted, cooperates with a pair of fixed contacts to energize the motor in one direction or the other for a given period of time depending upon the time of engagement of the contacts as said member moves in said path. With such structure it is seen that it is necessary to have flexible contact means so as to relieve the strain in the mechanism.

It is therefore an object of the present invention to provide a sensitive relay mechanism with a novel strain release mechanism whereby the contact mechanism or associated structure will not be strained as the contacts are made for different lengths of time.

Another object is to provide a strain release mechanism wherein one or the other of a plurality of contacts may be made and pushed back without unduly straining the other contact or other associated structure.

Further objects and advantages of the present invention will be in part apparent or pointed out in the accompanying specification and claims taken in view of the accompanying drawing, in which

Figure 1 is a diagrammatic showing of my invention applied to a heat control system,

Figure 2 is a detailed side view of the strain release mechanism mounted upon the operator therefor,

Figures 3 and 4 are views of my strain release mechanism in two or its active positions, and

Figure 5 is a view of a part of the contact operator embodying a modification of the strain release mechanism.

Figure 1 illustrates a system for controlling

the supply of heating fluid to a radiator 10 in accordance with the temperature of the space 11 in which the radiator 10 is located. A heating fluid which may be, for example, steam or hot water, is supplied to the radiator 10 through a supply pipe 12. This fluid after losing its heat, flows out of the radiator 10 through a return pipe 13. The supply of fluid to the radiator 10 through the pipe 12 is controlled by a valve 14. The valve 14 is operated by a control mechanism generally indicated at 15 which includes a rack 16 mounted on the valve stem and cooperating with a pinion 17. Supported by the rack 16 is a slider 18, which is moved across the slidewire resistance 19 in accordance with the position of the valve. The pinion 17 is driven by a motor 20, through a gear train schematically shown at 21. The motor 20 is provided with a pair of windings 22 and 23 which drive the motor in opposite directions. The operation of the motor 20 is controlled by a bridge circuit generally indicated at 24 whose output is amplified by a sensitive relay mechanism 25.

The bridge circuit 24 is supplied with electrical energy from a suitable source, shown in the drawing as a battery 30, connected to the input terminals 31 and 32, by conductors 33 and 34 respectively.

The upper left-arm of the bridge, as appears in the drawing, includes a fixed resistor 35, and a variable resistor 36. This arm of the bridge connects the input terminal 31 with an output terminal 37. The variable resistor 36 is provided so that the temperature at which the bridge will control may be adjusted.

The upper right arm of the bridge includes a resistor element 40, of nickel or some other material having an appreciable temperature coefficient of resistance. Although the system will be described as though the element 40 had a positive temperature coefficient, it will be readily apparent to those skilled in the art that an element having a negative temperature coefficient could be used with equal facility. One end of resistance element 40 is connected to the input terminal 31 through a conductor 41, and the other end of resistance element 40 is connected to the lower terminal of the slidewire resistance 19 by a wire 42. The upper right arm of the bridge circuit 24 also includes that part of the slidewire resistance 19 between its lower terminal, and the point of contact of slider 18 along the resistance wire 19. This point of contact is numbered 43 in the drawing and serves as one of the output terminals of the bridge circuit 24.

The lower left arm of the bridge includes a fixed resistance 44 connected to the input terminal 32 by a conductor 45 and the output terminal 37 by a conductor 46.

The lower right arm of the bridge circuit 24 includes a conductor 50, a fixed resistance 51, a conductor 52, and that portion of the slidewire resistance 19 between its upper terminal and the output terminal 43.

The output circuit of bridge 24 may be traced from the output terminal 37 to the movable output terminal 43. This output circuit includes a conductor 53, a coil 54 of a galvanometer generally indicated at 55, and a conductor 56 connected to the slider 18.

The coil 54 is mounted between the poles of the permanent magnet 60, and is attached to a pointer 61 which is deflected from a neutral position in accordance with the magnitude and direction of the current flowing through the coil 54. The pointer 61 moves parallel to a bar 62, against which it is periodically clamped by a clamping lever 63, pivoted at 64, and operated by a cam 65 acting against a cam follower 66 on the end of clamping lever 63 at the opposite side of pivot 64 from the portion which engages the pointer 61. The cam follower 66 is biased for engagement with the cam 65 by a spring 67.

The cam 65 is continuously rotated by a motor 70 connected through gears 71 and 72, the latter being attached to a shaft 73 on which the cam 65 is fixed. Also fixed on the shaft 73 is another cam 74. The cam 74 acts against a cam follower 76 mounted on a lateral projection of a supporting arm 77, which is mounted on a fixed pivot 81. The arm 77 is biased by a spring 80 so that the follower 76 engages the surface of the cam 74.

Pivottally mounted, as at 82, on the arm 77 is a switch operator 83. The switch operator 83 is provided with a long vertical extension 84 which is adapted to move transversely through the path of movement of the pointer 61. This switch operator 83 is biased for counter-clockwise rotation about the pivot 82 by a spring 85. Counter-clockwise rotation of the operator 83 with respect to the arm 77 is limited by a stop 86 which extends forwardly from the member 77. This stop 86 is arranged to engage a lower arm 87 of the switch operator 83.

During certain portions of the switching cycle rotation of the switch operator 83 is prevented by a brake member 90 which is biased into engagement with the member 83 by a spring 91. The brake member 90 is pivoted at 92 upon the arm 77. The brake is operated by means of a pin 93 which is secured to the cam 74. A brake cam 94 is disposed on the end of the brake arm 90. When the pin 93 engages the brake cam 94, the spring 91 will be compressed to release the brake 90. It is seen therefore that rotation of the cam 74 periodically operates to release the brake 90 with respect to the contact carrying member 83. Such operation takes place as the galvanometer pointer 61 is being engaged by the arm 84 to position the switch operator 83.

Mounted on the switch operator 83 is a switch member 95. The switch member 95 has an upper contact 96 and lower contact 97. The switch member 95 is secured at its lower end by means of a rivet or other suitable means to a forwardly extending arm 98 on the lower arm 87 of the switch operator 83 and is so secured to this arm 98 that the upper end of the member 95 is biased into engagement with a stop 99 extending for-

wardly from the switch operator 83. The contact 96 cooperates with a contact screw 100 to energize the coil 23 of the motor 20, and the contact 97 cooperates with a contact screw 101 to energize the other coil 22 of said motor through circuits to be traced hereinafter.

The cam 65 which operates the clamping lever 63 is provided with a riser portion 102, a high dwell portion 103 and a low dwell portion 104. 10 As the cam 65 rotates counter-clockwise, as indicated by the arrow in the drawing, the clamping lever 63 is held out of engagement with the pointer 61 as long as the follower 66 rides on the high dwell portion 103 of the cam. As the follower 66 moves down toward the low dwell portion 104 the lever 63 is moved into engagement with the pointer 61 by the spring 67. The lever 63 is maintained in engagement with the pointer 61 as long as the follower 66 is adjacent the low dwell portion 104 of the cam. When the follower 66 rides on the riser portion 102, the lever 63 is moved away from the pointer 61, thus freeing it.

The cam 74 which reciprocates the arm 77 through the follower 76 comprises a low portion 106, a riser portion 107, a first drop-off portion 108 of relatively short length and steep slope, a second drop-off portion 109 of considerably greater length and less slope, and an abrupt drop-off portion 110 connecting the portion 109 with the portion 106. The cam follower 76 is shown as just leaving its extreme left-hand position and engaging the low portion 106. As the follower 76 moves up the riser portion 107, the arm 77 is moved rapidly to the right carrying with it the switch actuating member 83. This moves the extension 84 out of the range of movement of the galvanometer pointer 61 which is then unclamped, and moves the contacts 96 and 97 to a position wherein the stationary contacts 100 and 101 may be engaged. As the follower 76 moves down the drop-off portion 108, the arm 77 is moved rapidly to the left for a short distance. As the follower 76 moves on down the slow drop-off portion 109, the arm 77 continues to move to the left, but at a considerably slower rate. When the follower 76 reaches the abrupt drop-off portion 110, the arm 77 is moved very rapidly to the left until the follower 76 engages the low portion 106 of the cam 74. During the last very rapid movement, extension 84 again moves within the range of movement of the galvanometer pointer 61 which is now clamped by the arm 63.

55 As the cam member 74 rotates to move the contact mechanism to and from the stationary contacts and back to take a new position in accordance with the positioning of the galvanometer needle 61, the brake mechanism 90 is likewise operated. By the arrangement shown the brake mechanism is adapted to be released to provide for free positioning of the contact mechanism as the contact mechanism moves to a left-hand position. At this time, the arm 84 at the upper end of the contact carrying member 83 engages the galvanometer needle 61. When this operation is taking place the pin 93 carried upon the cam member 74 is in engagement with the cam follower 94 upon the brake arm 90. At this time then, the brake will be biased in a counter-clockwise direction which will move the brake shoe from the semi-circular portion of the switch operator 83. In this manner it is seen that when the switch mechanism is being positioned in accordance with the position

of the galvanometer needle, the brake is released to thereby relieve the force acting upon the galvanometer needle. At this time the only force which will bias the arm 84 into engagement with the galvanometer needle will be that force exerted by the light spring 85.

Details of the construction of the strain release mechanism of the switches are shown in Figure 2. The operation of this mechanism is illustrated in Figures 3 and 4. Referring now to Figure 2, the member 95 is shown as comprising a first arm 120 which extends upwardly from the bracket 98 which is bent outwardly from the lower part of the contact carrying member 83. The arm 120 is secured at its lower end to the bracket 98. The upper portion of the member 95 is formed as a neck which supports a second arm 121 that extends downwardly toward the supported end of the arm 120. The lower end of the member 95 is so connected to the mounting member 98 that there is a bias at the upper end into engagement with the stop 99. The arm 121 is biased with a lesser force at its lower end into engagement with a stop 122. In this manner an arrangement is provided whereby the movable contacts 96 and 97 will engage the respective stationary contacts 100 and 101 with a given initial pressure. By such structure, the condition known as zero initial contact pressure is prevented.

Operation

It may be assumed that the temperature in the space has risen to a value above that desired. At this time the amount of resistance in the leg of the bridge including the variable temperature responsive resistance 40 will be varied. This variance in the resistance of the variable resistance 40 will result in a corresponding deflection of the galvanometer needle 61 to the left, for example. As the galvanometer needle 61 is positioned and the contact mechanism is operated back and forth, the contact mechanism will take a position in angular relationship to the movable arm 77 which carries the cam follower 76. Hence, as the galvanometer needle is moved toward the left the biasing spring 85 will cause the contact operator 83 to assume a position in counter-clockwise relationship with respect to the arm 77. At this time the contacts will take a position as contact 97 engages stationary contact 101 as illustrated in Figure 4, that is, the lower contact 97 will be moved closer with respect to the stationary contact 101 than the contact 96 with respect to the stationary contact 100. Hence, at this time, as the arm 77 is moved toward the right the contact 97 will engage the stationary contact 101, and as the entire contact mechanism is moved further toward the right the contact 97 will move toward the left with respect to the rest of the contact structure. At this time the arm 121 of the contact mechanism 95 will flex away from the stop 122. The bias in arm 120 is sufficient to keep the upper end thereof in engagement with the stop 99. Engagement of contacts 97 and 101 closes a circuit for the coil 22 as follows: From the secondary of a transformer 125, through conductor 126, contact operator 83, contacts 97 and 101, conductor 127, coil 22, and conductor 128 back to the transformer. The coil 22 will remain energized as long as the contacts 97 and 101 are closed to move the valve in a closing direction.

As the galvanometer needle is moved to its right-hand position, the contact operator 83 will take a position in clockwise relationship to the

moving arm 77. At this time the contacts when engaging the stationary contacts will take the position as illustrated in Figure 3 wherein the contact 96 is shown engaging the contact 100. Upon such engagement the upper end of the switch mechanism 95 will be bent away from the stop 99 and the lower end of the arm 121 will remain in engagement with the stop 122.

Engagement of contacts 96 and 100 closes a circuit for the coil 23 as follows: From transformer 125, through conductor 126, contact operator 83, contacts 96 and 100, conductor 128, coil 23, and conductor 129 back to the transformer. This circuit moves the valve 14 in an opening direction.

The configuration of the contact member 95 is such that approximately the same contact pressure will be obtained for each of the contacts 96 and 97. However, it will be obvious that the upper contact 96 will have a slightly greater pressure than the lower contact 97. The reason for this is that the upper end of the member 95 must be biased into engagement with the stop 99 with sufficient force to resist movement upon the bending back of the lower contact arm 121.

When the temperature responsive resistance located in the space 11 is satisfied, or when the valve has assumed a position wherein sufficient resistance is placed in series with the temperature responsive resistance 40 so that the galvanometer needle is in its mid position, then the contact mechanism may be so arranged that as it is moved to its extreme right-hand position neither of the stationary contacts 100 or 101 will be engaged. At this time, the valve 14 will remain in its adjusted position until such time as the ambient temperature varies to affect the temperature responsive resistance 40.

Referring now to Figure 5, wherein a modification of the contact structure is shown. The contact operator 83 is identical in every respect with the contact operator heretofore referred to. Mounted on the lower mounting bracket 98 is a contact member 130 comprising an upstanding arm 131, a neck portion 132, a lower contact arm 133 carrying a contact 134 and an upper contact arm 135 carrying a contact 136. With this structure the initial contact pressure of both the upper and lower contacts 134 and 136 may be the same, that is, the arm 131 may be biased toward the stops 99 and 122 with a given force. Because of the novel structure in this modification both contacts will be urged into engagement with their respective stationary contacts with the same force.

As one of the contacts 134 or 136 engages its corresponding stationary contact it will be obvious that that contact will be forced back and rotate both the upper and lower contact arms around the opposite stop, that is, the stop for the other contact, and thus flex both the contact arms 133 and 135 as well as the supporting arm 131. As both contacts are located equally distant from the neck portion 132, this force exerted when either contact is moved by a stationary contact because of movement of the contact operator 83 will be substantially identical.

The modification shown in Figure 5 is adapted to be applied into the system as illustrated in Figure 1. The operation of the device with this part provided thereto will be identical to the operation described in connection with the other form of my invention.

While I have shown two forms which my in-

vention may take, it will be obvious to those skilled in the art that many other adaptations of the device may be made. For example, it will be obvious to combine my novel strain release mechanism with other switching structures than that shown and described. For this reason I prefer not to be limited only to those forms which have been shown and described but by the spirit and scope of the appended claims and the prior art.

I claim as my invention:

1. In combination, a pair of spaced fixed electrical contacts, a pair of movable contacts cooperable therewith, movable means for oscillating said movable contacts to and from said stationary contacts, adjustable means for positioning said movable contacts angularly with respect to said movable means so that one of said movable contacts only may contact its cooperating stationary contact, and strain release means for mounting said movable contacts comprising, a flexible strip secured at one end, said strip having a free end mounting the first of said movable contacts, a portion of said strip secured at said free end and extending toward the mounted end of said strip, the free end of said portion mounting said second movable contact.

2. In combination, a pair of control contacts, an intermittently oscillatable member movable toward and away from said control contacts, an angularly adjustable member moved by said oscillatable member, a pair of actuating means mounted upon said adjustable member comprising a flexible strip mounted at one end, a first actuator at the free end thereof, a first stop to limit the movement of said free end in one direction, said free end being biased by a force into engagement therewith, a flexible member secured to said strip and extending toward said mounted end, a second actuator at the end of said flexible member, and a second stop to limit the movement of said last end in one direction.

3. In combination, a pair of actuatable control means, and means for intermittently actuating said control means comprising a flexible strip mounted at one end, a first actuator at the free end thereof, a first stop to limit the movement of said free end in one direction, said free end being biased by a force into engagement therewith, a flexible member secured to said strip and extending toward said mounted end, a second actuator at the end of said flexible member, and a second stop to limit the movement of said last end in one direction, said last end being biased into engagement therewith with less force than the bias of said free end.

4. A contacting device of the character described for mounting upon a support comprising, a member of flexible material mounted on said support at one of its ends, a first contact carried at the other end of said member, a flexible arm formed on said member and extending toward the mounted end thereof, and a second contact carried at the end of said arm.

5. In combination, a pair of fixed spaced control means, a pair of actuating means for said control means, and means connecting said actuating means comprising a flexible member, said member being formed so that one of said actuating means may flex away from its first position while the other actuating means remains in its first position.

6. In combination, a pair of control contacts, an intermittently oscillatable member movable toward and away from said control contacts, an

angularly adjustable member moved by said oscillatable member, and a pair of actuating means mounted upon said adjustable member comprising a flexible member, said member being formed so that one of said actuating means may flex away from its first position while the other actuating means remains in its first position.

7. In combination, a pair of fixed spaced electrical contacts, an actuator, a U-shaped flexible contact carrying member mounted at the end of one leg upon said actuator, a first contact mounted adjacent the bend of said U-shaped member, and a second contact mounted adjacent the end of the second leg of said U-shaped member.

8. In combination, a pair of fixed spaced electrical contacts, an actuator, a U-shaped flexible contact carrying member mounted at the end of one leg upon said actuator, a first contact mounted adjacent the bend of said U-shaped member, a second contact mounted adjacent the end of the second leg of said U-shaped member, and a pair of stops adjacent said contacts, said member being biased so that portions thereof will engage said stops with a predetermined force.

9. In combination, a pair of fixed spaced electrical contacts, an actuator, a flexible contact carrying member comprising, an arm mounted at one end on said actuator, a neck portion at the free end of said arm, an elongated portion extending substantially equidistant in opposite directions from said neck portion, and a pair of contacts carried near the ends of said elongated portion.

10. In combination, a pair of fixed spaced electrical contacts, an actuator, a flexible contact carrying member comprising, an arm mounted at one end on said actuator, a neck portion at the free end of said arm, an elongated portion extending substantially equidistant in opposite directions from said neck portion, a pair of contacts carried near the ends of said elongated portion, and a pair of stops adjacent said contacts, said member being biased so that portions thereof will engage said stops with a predetermined force.

11. The combination comprising a support, an actuating member mounted on the support and movable from a first to a second position, an adjustable member mounted on the said actuating member, a first pair of electrical contacts mounted on the support, a switch member mounted on the said adjustable member, a second pair of electrical contacts mounted on the switch member at opposite ends thereof for cooperation with the first pair of electrical contacts, a pair of stops mounted on the adjustable member for limiting the movement of the switch member in one direction, spring means normally biasing the switch member into contact with the stops, means for pivotally adjusting the adjustable member so as to vary the position of the second pair of contacts in relationship to the first pair of contacts so that upon movement of the actuating member from the first to the second position one of the second pair of contacts only may contact in engaging relation its cooperating contact in the first pair of contacts, and the said spring means holding the engaging contacts under spring tension.

12. The combination comprising a plurality of actuatable control contacts, a movable member, biasing means for the said member, means limiting the movement of the member in response to the said biasing means, means carried by the said member for actuating the said control contacts.

and adjustment means for varying the position of the movable member in relation to said contacts so that one of said actuatable control contacts only may be actuated by said actuating means.

13. The combination comprising a plurality of spaced electric contacts, a member for engaging the said contacts, adjustment means for varying the position of the member so that said contacts may be selectively engaged by the member at 10

opposite ends of said member, means for moving the said member in relationship to the contacts, and the member movable at one end in one direction upon engaging one of said contacts, and means limiting movement of the opposite end of said member responsive to the biasing effect of said one contact in such a manner as to prevent the engagement of said contacts by the opposite end of said member.

BENJAMIN CYR.
